UNITED STATES PATENT OFFICE.

CHARLES BALLREICH, OF PUEBLO, COLORADO.

LAWN-SPRINKLER.

1,116,536.

Specification of Letters Patent. Patented Nov. 10, 1914.

Application filed October 6, 1913. Serial No. 793,742.

To all whom it may concern:

Be it known that I, CHARLES BALLREICH, a citizen of the United States, residing at Pueblo, in the county of Pueblo and State 5 of Colorado, have invented a certain new and useful Improvement in Lawn-Sprinklers, of which the following is a full, clear, and exact description.

This invention is an improvement in 10 lawn sprinklers and has for its object the provision of a simple, cheap and easily constructed device which will distribute a spray throughout a truly semi-circular area.

In its preferred form the invention comprises means for connection to a hose combined with a hollow chamber into which the water is delivered, said chamber having a substantially semi-circular slot therein through which the water is ejected in the 20 form of a spray. Though I do not wish to limit myself in this regard, I prefer to form the chamber either as a cylinder, a frustum of a cone or a hemi-sphere with a cylindrical or frusto-conical extension—in other 25 words as a surface of revolution—and to locate this chamber with its axis at right angles to the direction of the entering water. I also prefer to locate the slot just below the top of the chamber so that said top may 30 aid in directing the water toward the slot. I have found, furthermore, that a more satisfactory spray is delivered if the inner edge of the lower surface of the slot be more distant from the axis of the chamber 35 than the outer edge of the upper surface of said slot. Such a shaped orifice located as described delivers a stream at an angle of about 45 degrees and the interference produced therein by the particles of water approaching the orifice from slightly different angles and by the slight inevitable roughness of the edges of the slot, will spray the water sufficiently to deliver it uniformly over the semi-circular area to be covered.

40 In order that water may leave a semi-circular slot uniformly in quantity and velocity throughout the length of the slot, it is necessary that the inertia of the water flowing in the feed pipe or hose, that is to say 45 the tendency of this water moving in a given direction to continue moving in that direction, be overcome as nearly as may be and that the discharge shall be such as results from the hydrostatic pressure of the water 50 only. The provision of a chamber which has its axis at substantially right angles to

the direction of the entering water, and preferably of a capacity greater than a similar length of hose, results largely in overcoming the inertia of the entering water. I 60 have found, however, that within practical sizes it is not convenient to entirely neutralize the entering inertia of the water and that to obtain a truly semi-circular discharge it is desirable to make the slot a little more than a semi-circle in length as indicated in the drawings. 65

Further and more particular advantages of my invention will later appear in the specification and be pointed out in the appended claims. 70

In the single sheet of drawings accompanying this application and forming a part hereof Figure 1 is a perspective of one form of sprinkler embodying my invention, 75 this form being capable of being conveniently made by casting; Fig. 2 is a central, vertical cross section of the form shown in Fig. 1; Fig. 3 is a central, vertical cross section of another form of my invention, this 80 form being capable of being readily made by pressing or spinning; and Fig. 4 is a central, vertical cross section through a still different embodiment of the invention, which form can be made either by stamping 85 or casting.

In the embodiment shown in Figs. 1 and 2, 5 represents a base, 6 a threaded connection for a hose, and 7 a chamber disposed at substantially right angles to the hose connection, which chamber in the form shown is substantially cylindrical though slightly conical toward the upper end, 9. A substantially semi-circular slot 8 is provided immediately below the upper end 9 of the 90 chamber 7. This slot may be formed in any convenient manner, as, for instance, by coring during the casting operation, but I have found it to be most conveniently made by grinding off the edge between the top 9 95 and the vertical wall 10 of the chamber 7. The ground surface makes a substantially equal angle with the horizontal and vertical so that the imaginary vertical and horizontal lines A and B (Fig. 2) clear both the side 100 and the top of the chamber. The dotted line C of Fig. 2 indicates the axis of the chamber 7 and points out clearly that the slot 8 is ground through more than a semi-circle. This is for the reason, as previously 105 stated, that within practical limits of size of the chamber 7 the direction imparted to

the water by its passage through the hose can not be entirely overcome and in order to obtain a truly semi-circular spray I have found it necessary to make the slot a little 5 greater than a semi-circle.

In Fig. 3 I have shown a modification in which the chamber 11 is substantially a hemisphere, a short cylindrical shaped projection 12 being formed thereon in which to make 10 the slot or orifice 13. This slot also may be made by grinding or filing away the metal, which in this form is preferably stamped or spun and therefore thin. The angle of grinding, to give the same relation 15 between the sides and top of the slot, and the circular length of the slot should preferably be the same as those indicated in connection with the modification shown in Fig. 1.

In Fig. 4 I have illustrated a modification 20 which may be made either of cast or pressed metal and in which the slot 14 may readily be sawed or cored out and still maintain the inner edge of the lower portion of the slot farther away from the axis of the chamber 25 than the lower edge of the upper part of the slot—which is the desirable relation as pointed out above. In this form, which is that of a truncated cone, the sides of the chamber are inclined and the inclination to 30 be given thereto is determined by two factors, namely, the thickness of the metal employed and the width of the slot to be made. The thicker the metal is made with the same width of slot, the greater the inclination 35 which must be given to the sides; and the wider the slot, with the same thickness of metal, the less inclination to the vertical need be given to the sides. It will be obvious that only the upper portion of this modification 40 (the part wherein the slot is to be made) need be given the particular inclination whereby a horizontal incision will produce a slot through which the vertical F can be dropped without touching the sides 45 and that the remainder of the chamber may

be given any convenient shape without departing from my invention.

If it is desired to produce an added spraying action over that resulting from the use of a comparatively clean edged slot, the 50 edges of the slot may be roughened or serrated to obtain this end.

Having thus described my invention, what I claim and desire to secure by Letters Patent is:

1. In a lawn sprinkler, a chamber having the lateral surface of a solid of revolution and a top and bottom disposed in planes at right angles to the axis of said chamber, the top and lateral surfaces meeting for approximately 60 a semi-circle only whereby there is formed a substantially semi-circular slot immediately below said top, the edges of the top and lateral surface adjacent the slot being so beveled that the lower edge of said slot is farther distant from the axis of said chamber than the upper edge thereof.

2. In a lawn sprinkler, a chamber having the lateral surface of a solid of revolution and a top and bottom disposed in planes at 70 right angles to the axis of said chamber, the top and lateral surfaces meeting for approximately a semi-circle only whereby there is formed a substantially semi-circular slot immediately below said top, the edges of 75 the top and lateral surface adjacent the slot being so beveled that the lower edge of said slot is farther distant from the axis of said chamber than the upper edge thereof, and means in the lateral surface of said chamber 80 adjacent the bottom thereof and on the side opposite said slot for admitting water to said chamber.

In testimony whereof, I have hereunto signed my name in the presence of two witnesses.

CHARLES BALLREICH.
